UNITED STATES PATENT OFFICE.

FREDERICK A. REDMON, OF SAN FRANCISCO, CALIFORNIA, ASSIGNOR OF
ONE-HALF TO WILLIAM R. SMEDBERG, OF SAME PLACE.

CHAIN-TIGHTENER.

SPECIFICATION forming part of Letters Patent No. 596,618, dated January 4, 1898.

Application filed August 10, 1897. Serial No. 647,733. (No model.)

To all whom it may concern:

Be it known that I, FREDERICK A. REDMON, a citizen of the United States, residing at San Francisco, in the county of San Francisco and 5 State of California, have invented certain new and useful Improvements in Chain-Tighteners; and I do hereby declare that the following is a full, clear, and exact description thereof.

My invention is a mechanical device for 10 tightening chains used in binding and securing loads of lumber, &c., the object being to provide a portable tightening apparatus which can be readily attached to and then 15 form part of the binding-chain and be carried with such chain on the wagon in readiness for use. The construction of the tightener also renders it self-locking or non-slipping to the backward strain of the chain without rendering it necessary to employ adjustable 20 clutches or any independent locking means. For tightening the binding-chains around loads of lumber, &c., the means commonly employed is a bar by which the chain is twisted to take up the slack; but in practice 25 this device is only of temporary use, since the chain soon becomes loose again.

My invention is fully hereinafter described and is shown in the accompanying drawings, in which—

30 Figure 1 is a vertical cross-section. Fig. 2 is a horizontal section. Fig. 3 is a cross-section at right angles to Fig. 1. Fig. 4 is a side elevation of the sprocket when in engagement with the chain.

35 A represents an ordinary link chain which may be supposed to encircle a load of any character. One end of the chain is hooked to the base-plate B of the tightener preferably by a hook 1 and clevis 2. The free end 40 of the chain after passing around the load is guided over the base-plate preferably in a channel 3, formed in such base-plate, Fig. 3. To the base is bolted a hood C, which incloses the mechanism and also, in connection with 45 the base, provides bearings for the pins or shafts which apply the power used in tightening. Such a shaft D carries a worm E and has a square end to receive a crank. Another shaft F, journaled in the hood and in a 50 plane at right angles to shaft D, carries a

gear G, which engages with the worm, from which it derives a rotary motion. Secured upon the shaft F is a sprocket H, having recesses 4, which engage with the chain-links in succession when power is applied, the chain 55 being guided straight by the base and the links being tangent to the sprocket. The free end of the chain passes through holes 5 6 in the hood and may remain free, since such chain is locked by the tightener. 60

The screw-gearing shown is self-locking and non-slipping and cannot be caused to yield by the backward strain of the chain, since it requires a positive turning of the operating-shaft to move it. 65

I do not limit myself to the details of construction shown and described, nor to the exact form of gearing, which, nevertheless, I prefer to use. Within the limits of the following claims modifications and equivalents 70 can be employed without departing from the spirit of my invention.

What I claim as new, and desire to secure by Letters Patent, is—

1. A chain - tightener consisting of a 75 sprocket, non - yielding gearing for driving and holding the same, and means for guiding the free end of the chain in engagement with said sprocket.

2. A chain - tightener comprising a base- 80 plate to which one end of the chain is secured, and along which the free end of the chain is guided, a sprocket mounted upon said base and engaging the chain-links, and means for turning and holding said sprocket. 85

3. A chain - tightener comprising a base-plate, having means for attaching one end of the chain, a hood secured to said base, a worm-shaft, and a counter-shaft having a pinion 90 engaging with said worm and carrying a sprocket to engage with the chain-links.

4. In a chain-tightener, and in combination, a base-plate having means for attaching one end of a chain, and a channel-guide for the free end of said chain, a sprocket adapted 95 to engage the chain-links, and non-yielding gearing for operating and holding said sprocket.

5. In a chain-tightener, and in combination a base-plate, a hood secured thereto, and 100

having openings for the passage of the free end of a chain whose other end is secured to said base, a worm-shaft journaled in said hood and base, and a driven shaft journaled in the hood and carrying a sprocket adapted to engage the chain-links.

5 In testimony whereof I have affixed my

signature, in presence of two witnesses, this 31st day of July, 1897.

FREDERICK A. REDMON.
